FRAME OF A VULCANIZING MACHINE

Sidney John Herbert, Hayes End, England, assignor to Stenor Limited, Richmond, England

Application June 2, 1952, Serial No. 19,995
In Great Britain January 15, 1952

Term of patent 14 years

(Cl. D81—1)

To all whom it may concern:

Be it known that I, Sidney John Herbert, a subject of the Queen of Great Britain, of 80 York Avenue, Hayes End, Middlesex, England, have invented a new, original, and ornamental Design for a Frame of a Vulcanizing Machine, of which the following is a specification, reference being had to the accompanying drawings, forming part thereof:

Fig. 1 is a perspective view of a frame of a vulcanizing machine, showing my new design;

Fig. 2 is another perspective view thereof taken opposite Fig. 1;

Fig. 3 is a side elevational view thereof; and

Fig. 4 is a top plan view thereof.

I claim:

The ornamental design for a frame of a vulcanizing machine, as shown,

SIDNEY JOHN HERBERT.
